UNITED STATES PATENT OFFICE

92,921

DESIGN FOR A LAMP

Ambrose D. Olds, Wichita, Kans.

Application May 18, 1934, Serial No. 51,832

Term of patent 7 years

To all whom it may concern:

Be it known, that I, AMBROSE D. OLDS, a citizen of the United States of America, residing at Wichita, in the county of Sedgwick and State of Kansas, have invented a new, original, and ornamental Design for Lamps, of which the following is the specification, reference being had to the accompanying drawing, forming a part thereof.

The figure is a front elevational view of the lamp, showing my new design.

I claim:

The ornamental design for a lamp as shown.
In testimony thereof, I affix my signature.

AMBROSE D. OLDS
